UNITED STATES PATENT OFFICE.

NATHANIEL G. SCOTT, OF NEW ORLEANS, LOUISIANA.

PILE-DRIVER.

1,375,738.

Specification of Letters Patent. Patented Apr. 26, 1921.

Application filed October 7, 1920. Serial No. 415,420.

To all whom it may concern:

Be it known that I, NATHANIEL G. SCOTT, a citizen of the United States, residing in New Orleans, in the parish of Orleans and 5 State of Louisiana, have invented certain new and useful Improvements in Pile-Drivers, of which the following is a specification.

This invention relates to pile drivers of the class known as "pendulum drivers" in 10 which the "leads" or guides for the hammer are so supported that they may be set at different angles in order to drive the piles either vertically or diagonally for the purpose of providing what are termed "batter 15 piles."

Heretofore pendulum pile drivers have been limited in their range of operation, being adapted only to drive batter piles which are slightly inclined, but according to my 20 invention I am enabled to drive such piles at any desired angle.

In carrying out my invention, I provide what are termed "shears" which serve to support the leads or guides for the hammers 25 and which comprise a vertical front frame consisting of upright side pieces and cross pieces and an inclined rear frame which braces the front frame and which consists of trussed, diagonal side beams which are connected to the front frame by horizontally 30 arranged pieces of different lengths. The leads or guides for the hammer are supported by the front frame of the shears and consist of vertical side pieces arranged a 35 suitable distance apart and faced on their inner sides with channel irons which provide wearing surfaces for the hammer. The side pieces are connected by yoke blocks set at suitable intervals. The leads are suspended from the top of the front frame of 40 the shears, being provided at their upper ends with a trolley which is adapted to travel sidewise on a rail attached to the shears. Means is provided for moving the 45 leads sidewise in the shears to set them in different vertical planes, and provision is also made for setting the leads at different angles in the shears within certain limits. When it is desired to set the leads at angles 50 which are more oblique I employ laterally extending lead supports which are connected with the cross pieces of the frame and which may be so connected with the leads as to hold them securely when once adjusted. 55 Other features of my invention will be hereinafter described.

In the accompanying drawings:

Figure 1 is a side elevation of a pile driver embodying my improvements supported on a barge.

Fig. 2 shows a rear elevation of the upper portion of the leads.

Fig. 3 is a perspective view of the front of the upper portion of the leads.

Fig. 4 is a front elevation of the pile 65 driver.

Fig. 5 shows a local section on the line 5—5 of Fig. 4.

Fig. 6 shows a local section on the line 6—6 of Fig. 4.

Fig. 7 is a top plan view of the pile 70 driver.

Fig. 8 is a detail sectional view on the line 8—8 of Fig. 4.

Fig. 9 is a detail sectional view, showing 75 the manner of connecting some of the parts.

Figs. 10—15, inclusive, are diagrams, illustrating various positions in which the leads may be set to drive piles at various 80 angles.

The drawings show my improved pile driver mounted and supported by a barge A, but it may be otherwise mounted and supported in any well known way. The shears of the driver comprise a front frame B and a rear frame B'. The front frame consists of vertical side pieces b, secured at the bottom to a moon beam C and at the top connected by a cross piece b', over which is arranged and secured a top cross piece 90 T, the opposite ends of which project beyond the sides of the shears. Between the top and bottom of the frame there are horizontal cross pieces D which are bolted to the sides of the frame, as indicated at d, 95 and these cross pieces are formed with a series of holes d', as indicated in Fig. 4. The cross pieces D, it will be observed, extend beyond the sides of the shears and they support laterally extending lead supports E, 100 each of which is formed with a series of holes e and each of which is pivotally connected at e' to a cross piece D.

The rear frame B' comprises diagonally arranged beams c secured at their upper 105 ends c' to the front frame and strengthened by truss pieces c² in any suitable way. The rear frame is also connected with the front frame by connecting pieces c³. Guy cables F are employed, being connected to the 110 upper ends of the shears and to the rear end of the barge A.

The leads or hammer guides G comprise vertical side pieces g held a suitable distance apart by yoke blocks H which are bolted to the side pieces g at g' and furring strips g^2 are secured to the sides g on opposite sides of the yoke blocks.

In order to provide wearing surfaces for the hammer, channel irons K are attached to the inner faces of the sides, as indicated 10 in Figs. 5 and 6.

The hammer L is adapted to reciprocate endwise of the leads and to operate on a pile P in well known ways.

To the upper ends of the side pieces g is 15 secured a horizontal top piece O from which extends rearwardly and downwardly side pieces o which support, at their lower ends, a trolley frame R comprising two short pieces r separated by an intermediate piece 20 r' . The trolley frame carries a trolley wheel S which rests on a rail s on the top cross piece T of the shears.

The hammer L is supported by a cable U which extends over pulleys u , u' on the top 25 piece O and trolley frame R, respectively, and under a pulley u^2 on the barge to a winch U' operated by an engine W.

By these means the hammer may be raised and dropped in well known ways, but in 30 this connection I would say that a steam hammer or ram of any well known kind may be used instead of a drop hammer.

In Fig. 4, I have illustrated what is known as a "hog chain" Y which is attached at its 35 opposite ends to the shears and held under tension. On the central portion of this chain rests a block y depending from the top cross piece b' of the frame. This arrangement serves to support the central part of 40 the shears frame and prevent sagging.

In order to strengthen the upper part of the leads I provide brace rods Z which are attached at their upper ends to the trolley frame R, extend downwardly therefrom, are 45 then bent inward and downward, at z , and are attached to the furring strips g^2 , as most clearly indicated in Fig. 3.

In order to shift the leads and the hammer laterally to drive in different vertical 50 planes, I provide cables X, X' which are attached to the upper part of the shears, pass over suitable guide pulleys or sheaves and connect with the windlass or drum U'. By these means the leads and hammer may be 55 shifted laterally in the manner indicated diagrammatically in Figs. 10 and 11 to operate in different vertical planes. When thus adjusted the leads may be pinned to the cross piece D as indicated at x' and in 60 this way the leads may be adjusted not only to operate in different vertical planes but also at different angles within certain limits. But by employing lead supports E, I am enabled to so set the leads that batter piles 65 may be driven at any desired angle up to

45° and beyond. When the parts E are not in use they may be folded over upon the cross piece D, as indicated at the upper left-hand side of Fig. 4 and also in Figs. 10-13, but when it is desired to drive piles at a decided angle, one or more of the parts E may be swung outward and secured in place by a pin or pins x .

By referring to Figs. 14 and 15, it will be observed that by different adjustments the 75 leads may be set at various angles so that batter piles may be driven at any desired inclination.

I claim as my invention:—

1. A pile driver comprising shears 80 composed of a vertical front frame having side pieces, a cross piece secured to the upper ends of the side pieces, a moon beam to which the lower ends of the side pieces are secured, a vertical intervening series of horizontally arranged cross pieces arranged at intervals between the top and bottom of the shears, and which have extensions projecting beyond the side pieces, hammer leads, a trolley frame connected to the upper end of 85 the shears, and supported on the top of the shears, means for moving the trolley across the shears, and means for securing the leads to those portions of the intervening cross pieces between the sides of the shears and 90 also to their extensions.

2. A pile driver comprising shears 95 consisting of vertical side pieces, a moon beam to which they are secured at their lower ends, a top piece secured to the upper ends of the 100 side pieces and extending horizontally beyond them, a vertical series of horizontally arranged intervening cross pieces secured to the sides of the shears and having extensions projecting beyond them, hammer leads supported on the top of the shears, means for moving the leads horizontally on top of the 105 shears, and means for securing the leads to the intervening cross pieces of the shears between the side pieces thereof and also to 110 their extensions.

3. In a pile driver, a shear frame consisting of vertical side pieces, a moon beam to which the lower ends of the side pieces are secured, a top piece secured to the upper 115 ends of the side pieces, intervening cross pieces secured to the sides of the frame at different levels between their upper and lower ends, leads supported on the shears, extensible lead supports carried by the ends 120 of the intervening cross pieces, and means for securing the hammer leads to said supports.

4. In a pile driver, the combination of 125 shears comprising side pieces, top and bottom cross pieces and intervening cross pieces having extensible lead supports at their ends, means for pivotally connecting said lead supports to the intervening cross pieces, hammer leads supported by the shears, 130

means for moving the hammer leads transversely of the shears, means for moving the hammer leads about a horizontal axis above the shears, and means for attaching the hammer leads to said lead supports.

5. In a pile driver, the combination with the side pieces and cross pieces of the shear frame of a top piece extending at opposite ends laterally from the shear frame, leads 10 provided with means for attaching them to the cross pieces of the shear frame, a trolley carried by the upper end of the leads, sup-

ported by the top cross piece of the frame and movable sidewise thereon, laterally extending lead supports pivotally connected 15 with the cross pieces of the shear frame, means for holding said supports in adjusted positions, and means for attaching the hammer leads to said supports to assume varied angles for driving batter piles.

20 In testimony whereof I have hereunto subscribed my name.

NATHANIEL G. SCOTT.
